No. 858,287.

PATENTED JUNE 25, 1907.

H. T. HIGINBOTHAM.
FIREPROOF DOOR OR SHUTTER.
APPLICATION FILED AUG. 23, 1906.

FIG. 3.

Attorneys

UNITED STATES PATENT OFFICE.

HENRY T. HIGINBOTHAM, OF NEW ORLEANS, LOUISIANA.

FIREPROOF DOOR OR SHUTTER.

No. 858,287.

Specification of Letters Patent.

Patented June 25, 1907.

Application filed August 23, 1906. Serial No. 331,813.

To all whom it may concern:

Be it known that I, HENRY T. HIGINBOTHAM, a citizen of the United States, residing at New Orleans, in the parish of Orleans and 5 State of Louisiana, have invented certain new and useful Improvements in Fireproof Doors or Shutters, of which the following is a specification.

This invention contemplates certain new 10 and useful improvements in fire proof doors and shutters, and the object of the invention is to provide an improved construction of device of this character which will embody the characteristics of lightness and strength 15 but susceptible to contraction and expansion without any liability of warping and which will be provided with air spaces that will enable the door or shutter to successfully withstand a fire no matter upon what side 20 of the door or shutter the fire might occur.

With this and other objects in view as will 25 more fully appear as the description proceeds, the invention consists in certain constructions, and arrangements of the parts hereinafter described and particularly pointed out in the appended claims.

For a full description of the invention and the merits thereof and also to acquire a knowledge of the details of construction of the 30 means for effecting the result, reference is to be had to the following description and accompanying drawings, in which:

Figure 1 is a front elevation of a window, illustrating my invention as embodied in a 35 pair of hinged shutters, one of said shutters being open and the inner side thereof partially broken away. Fig. 2 is a horizontal sectional view of one of the shutters. Fig. 3 is a similar view of a portion of one of the 40 shutters on an enlarged scale. Fig. 4 is a vertical sectional view on the line x—x of Fig. 2.

Corresponding and like parts are referred to in the following description and indicated 45 in all the views of the drawings by the same reference characters.

The improved door or shutter of my invention comprises three layers of corrugated metal, namely, two outside layers designated 50 1 and 2, the corrugations of which extend longitudinally, and an intermediate layer 3 between the other two layers, the corrugations of the intermediate layer extending obliquely preferably at an angle of forty-five 55 degrees to the corrugations of the two outside layers.

In the preferred construction, the outer layer 1 is located adjacent the interior of the building when the device, if a shutter, is closed.

Hereinafter therefore, to distinguish the layer 1 from the layer 2 while both are exterior or outside layers with respect to the layer 3, I shall refer to the layer 1 as the inner layer, the layer 2 as the outer layer, and the 60 inside layer 3 as the intermediate layer.

Between the inner layer 1 and the intermediate layer 3 a sheet of asbestos 4 is placed.

As shown particularly in Fig. 3, the inner layer 1 is provided with a flat marginal extension 1^a, projecting beyond the other layers above mentioned, and to the outer edge of this marginal extension 1^a, an angle iron binding strip 5 is secured. The outstanding member 5^a of the angle iron binding strip 5 70 is spaced from the corrugated layers 1, 2 and 3, and in this space is secured a corrugated strip 6 with its corrugations extending longitudinally. The strip 6 is also provided with a flat marginal extension, designated 6^a, said 75 extension being interposed between the main portion of the angle iron binding strip 5 and the extension 1^a of the inner layer 1. The opposite edge or margin of the corrugated strip 6 is also slightly flattened and is interposed between the main corrugated layers, a row of rivets 7 being inserted through each 80 corrugation so as to secure all the corrugated layers together, including one edge of the strip 6, and another row of rivets 8 being inserted through the main portion or member 85 of the angle iron binding strip 5, through the extension 1^a of the layer 1 and through the interposed marginal extension 6^a of the strip 6. This produces an almost solid door with 90 three series of air spaces or channels, namely, a series on each side of the diagonally corrugated intermediate layer 3 and a diagonally extending series produced by said intermediate layer 3 and the asbestos sheet 4. In 95 addition to these air channels or spaces, air spaces are provided to extend longitudinally at the margins of the shutter or door, by means of the corrugated strips 6.

From the foregoing description in connection with the accompanying drawings, it will be seen that the construction produced by my invention will allow a free circulation of draft that will keep each layer cool in the event of a fire against either side of the shutter or door, and the angle iron 5 will prevent the door or shutter from warping, while the 100 105 110

obliquely corrugated intermediate strip will permit the expansion and contraction of the door or shutter without warping or other injury thereto, and the entire structure will be 5 practically solid, while at the same time it will combine the characteristics of lightness with durability.

While the accompanying drawings illustrate my invention as embodied in a pair of 10 hinged shutters, it is obvious that it is not limited thereto, as it is equally applicable to sliding shutters and doors.

Having thus described the invention, what is claimed as new is:

15 1. The herein described fire proof closure, consisting of an inner layer and an outer layer both of which are corrugated and have their corrugations extending longitudinally, an intermediate corrugated layer, the corruga- 20 tions of which extend obliquely to the corrugations of the other two layers, and an asbestos sheet interposed between the inner layer and the intermediate layer, whereby there are produced three intermediate series of air 25 channels namely, the longitudinally extending series between the outer layer and the intermediate layer, the longitudinally extending series between the asbestos sheet and the inner layer, and the obliquely extending se- 30 ries between the asbestos sheet and the intermediate layer.

2. The herein described fire proof closure, comprising corrugated layers, one of which is provided with marginal extensions, angle 35 bars secured to said extensions, and corrugated strips secured to said angle bar and marginal extensions and lying between the angle bar and the corrugated layers.

3. The herein described improved fire proof closure, comprising corrugated layers, one of which is provided with flat longitudinal extensions, angle bars secured to said extensions with one member outstanding therefrom, and corrugated strips located in the space between said outstanding members of 40 the angles and the said corrugated layers, said corrugated strips being also provided with flat marginal extensions interposed between the angle bars and the first named marginal extensions. 45

50 4. The herein described improved fire proof closure, comprising corrugated layers, one of which is provided with flat longitudinal extensions, binding strips secured to said extensions, and corrugated strips located be- 55 tween said binding strips and the said corrugated layers and secured to the latter and to the said flat extension of one of said layers.

5. The herein described fire proof closure, comprising corrugated layers, one of which is provided with marginal extensions and spaced from the main portion of the corrugated layers, and corrugated strips provided with side edge extensions, one of which is inter- 60 posed between the adjacent binding strip and the marginal extension of one of the corrugated layers, and the other of which is inter- 65 posed between the marginal extension of one of the layers and the edges of the other layers.

In testimony whereof I affix my signature 70 in presence of two witnesses.

HENRY T. HIGINBOTHAM. [L. s.]

Witnesses:

GEORGE W. SHERMAN,
HENRY C. GAUSE.
